UNITED STATES PATENT OFFICE.

CLARENCE P. HOLLISTER, OF NEW YORK, N. Y.

COMPRESSION PACKING-RING AND VALVE.

1,362,312.

Specification of Letters Patent. Patented Dec. 14, 1920.

Application filed July 2, 1917. Serial No. 178,089.

To all whom it may concern:

Be it known that I, CLARENCE P. HOLLISTER, a citizen of the United States, residing at New York, in the county of New York and State of New York, have invented certain new and useful Improvements in Compression Packing-Rings and Valves, of which the following is a specification.

My invention relates to packing rings which are more especially adapted for use in connection with revoluble sleeve valves of internal combustion engines.

The main object of my invention is to provide an expansion packing ring for maintaining the proper compression in the combustion chamber and preventing the leakage of gas during the explosion and the compression strokes of the piston, possessing the self-cleaning feature of the split ring in removing any carbon or other deposits which may accumulate at the edges of the ports, but with the further advantage that the ring is not completely severed and may be provided with a plurality of slots extending partially across the ring, each of which is closed at one end.

In the accompanying drawings, Figure 1 is a vertical sectional view through the cylinder of an internal combustion engine showing an embodiment of my invention; Fig. 2 is a side elevation, partly broken away, of the sleeve valve and compression ring shown in Fig. 1; Fig. 3 is a transverse section on the line 3—3 of Fig. 1; Fig. 3^a is an enlarged fragmentary section on the line 3^a of Fig. 1; Figs. 4 and 5, are perspective views of the compression shell showing different ways of cutting the slots in the shell; and Fig. 6 is a developed diagram showing a modified arrangement of the slots.

The engine cylinder 1, which may be provided with the usual jacket 2, to provide a passage 3 for the circulation of cooling water, is bolted to a base 5 constituting the crank case. The revoluble sleeve valve 10 rests upon a bearing ring 12, carried by a web 14, extending inwardly from the upper part of the crank case.

The sleeve valve may be rotated at a speed proportionate to the speed of the crank shaft in any suitable manner, as by means of a chain 15, connecting a sprocket wheel 16 keyed to the crank shaft 17, and

a sprocket 18 on the countershaft 19, which carries a worm 20 meshing with the gear 55 teeth 21 on the sleeve valve.

The lubrication of the valve is effected by the splash of the crank 23 in the oil maintained in the crank case, which throws the oil upwardly against the interior walls 60 of the sleeve 10 at each reciprocation of the piston 25. A portion of the oil passes through the apertures 26 into the spiral groove 27 and is carried upwardly by the action of the spiral groove during the rotation 65 of the sleeve over the inner wall of the cylinder 1, thereby maintaining a film of oil between the surfaces of the sleeve and cylinder.

The cylinder head 30 projects within the cylinder below the ports and is provided with passages 31 and 32 registering respectively with the intake port 34 and the outlet port 35. The rotary valve is provided with ports 36, 37 which register alternately with 75 the intake and exhaust ports. In order to prevent the gases from passing around the upper edge of the valve shell into the ports during compression and when exploded, a compression shell 40 is disposed between 80 the valve casing and the cylinder, the upper end of the valve casing having a reduced diameter to provide an annular recess therefor. The compression shell is provided with openings 41, 42 in register with the valve ports and is secured to the valve in any suitable manner, as by means of pins 43. The gases under compression and explosion are also prevented by the compression shell 85 from passing downwardly between the valve casing and the cylinder wall which is essential to the maintenance of the film of lubricating oil therebetween.

It has heretofore been proposed to employ a compression shell which is split or cut entirely across. I have found that I can retain the advantages of a split shell or cylinder, while obviating certain of its defects and obtain other advantages by employing an integral shell having a plurality 100 of slots extending partially across from opposite edges.

In Figs. 2 and 4, I have shown the slots 50, 50^a extending diagonally and in Fig. 5, parallel to the axis or perpendicular to the 105 edges of the shell. These oppositely extend-

ing parallel slots permit the shell to be compressed sufficiently to be inserted into the engine cylinder and afterward expand into a tight contact with the cylinder wall. The 5 slot 50 extends downwardly from the upper edge of the shell and is closed at its lower end so that no gas can escape between the valve and the shell at the bottom. There can be no escape of gas at the top as the 10 cylinder head is closed. The slot 50', however, extends upwardly from the lower edge of the shell thus affording a channel for the escape of the gas at the bottom, which would pass downwardly between the walls 15 of the valve sleeve and the cylinder, following also the spiral groove 27, and thereby driving out the film of lubricating oil. To prevent the downward escape of gas in this manner, I close the lower end of the slot 20 50'. I insert a small closure member 53 in a slot or recess extending transversely across the slot. To still further provide against any passage of gases downwardly between the valve cylinder and the shell which might 25 escape under the compression shell, I may provide one or more expansion rings 54, seated in a groove or annular recess in the valve.

In Figs. 2, 3 and 4, I have shown the 30 slots arranged at only one small section of the ring, the remainder of the ring being unslotted. This makes the ring very staunch and stiff and the elasticity of the metal throughout the whole of the unslotted portion 35 resists any tendency to compression, or in other words, nearly the whole of the ring exerts its elasticity to force the ring out against the inner periphery of the cylinder. In Fig. 6 I have shown another form in 40 which the partial slots are placed upon either side of the ports. Here also only a very small proportion of the peripheral wall of the ring is slotted, substantially two-thirds of the metal being unslotted as will 45 be observed by reference to the cross-sectional view, Fig. 3.

The operation and function of the compression shell will be understood from the above detailed description. It is secured by 50 pins 43, or in other suitable manner, to the valve cylinder and rotates with it, fitting tightly against the cylinder wall and effectually preventing any escape of gases during compression and explosion. The slots 55 50, 50' in the compression shell not only permit the expansion of the shell against the cylinder wall, but during the rotation of the shell the edges of the slots scrape away any carbon deposits or other foreign 60 matter from the margins of the ports. I am thus enabled to combine with the means for preventing leakage a self-cleaning feature which effectually prevents any accumulation of deposits with the attendant loss 65 of efficiency and stoppage for cleaning and

repairs. It is evident also that this greatly reduces the wear of the moving parts and prolongs the life of the machine. I have illustrated several modifications but it will be apparent to engineers that other changes 70 and variations may be made within the scope of my claims.

I claim:—

1. In an internal combustion engine, a revoluble compression or packing ring, comprising an integral cylindrical shell having a series of ports formed therein, and a yielding portion formed by a plurality of slots 75 extending partially thereacross from opposite edges, the major portion of the ring 80 being unslotted.

2. In an internal combustion engine, a compression or packing ring, comprising an integral cylindrical shell having a series of ports formed therein, a plurality of slots 85 extending partially thereacross, one of said slots extending from one edge and another slot extending from the opposite edge, and a closure member seated in a recess or aperture in the shell extending transversely of 90 the slot which extends from the lower edge of the shell, to thereby prevent the escape of gases downwardly therethrough.

3. In an internal combustion engine, a compression or packing ring, comprising an 95 integral cylindrical shell having a series of ports formed therein, and a slot upon each side of one of said ports, the ring being otherwise unslotted, said slots extending from opposite edges of the shell partially 100 thereacross.

4. In an internal combustion engine, a compression or packing ring, comprising an integral cylindrical shell having a series of ports formed therein, slots upon each side 105 of said ports extending partially across the shell, the slots adjacent each port upon opposite sides thereof extending from opposite edges of the shell, and closure members seated in recesses or apertures in the shell 110 extending transversely of the slots which extend from the lower edge of the shell.

5. In an internal combustion engine, comprising a cylinder having inlet and outlet ports, a revoluble sleeve valve disposed in 115 said cylinder and provided with openings to register alternately with said ports and a compression shell surrounding the upper end of said sleeve valve and revoluble therewith and having openings in alignment with 120 said openings therein, said shell being an integral cylinder and having a plurality of slots extending from opposite edges thereof to form a yielding portion, the major portion 125 of the ring being unslotted.

6. In an internal combustion engine, comprising a cylinder having inlet and outlet ports, a revoluble sleeve valve disposed in 130 said cylinder and provided with openings to register alternately with said ports, a com-

pression shell surrounding the upper end of said sleeve valve and having openings in alinement with said openings therein, said shell being an integral cylinder and having 5 a plurality of slots extending from opposite edges thereof, closure members seated in recesses or apertures in the shell extending

transversely of the slots which extend from the lower edge of the shell, and a packing ring located in an annular recess in the 10 sleeve valve and bearing outwardly against the shell and against said closure members.

In testimony whereof I affix my signature.

CLARENCE P. HOLLISTER.
